AUTOMATIC LADLING MEANS

Albert S. Kux, Chicago, Ill., assignor to Kux Machine Co., Chicago, Ill., a corporation of Illinois

Application November 15, 1948, Serial No. 60,090

4 Claims. (Cl. 22—79)

1

This invention relates to automatic ladling means for transferring liquid materials.

For the purpose of this disclosure, the invention will be described as applied to a die casting machine, but it will be distinctly understood that the scope of this invention is not limited to the particular application and illustrative use of the invention.

Heretofore, in the operation of cold chamber die casting machines, a charge of molten metal was manually conveyed and ladled by an operator from the melting furnace associated with the machine into the injection cylinder. The character of the operation was disagreeable, highly fatiguing and dangerous from the standpoint of the operator, in view of the high temperatures surrounding the immediate zone of the melting furnace where the operator was required to stand and the liability of being injured by the spattering of molten metal. Additionally, in view of the human element present the quantity of each charge could lack uniformity and could result in imperfect castings. Accordingly it is an object of my invention to provide automatic means for conveying and ladling charges of molten metal from the melting furnace into the sprue of the injection cylinder of a die casting machine.

Another object of my invention is the provision of means of the foregoing character which operates to deliver to the sprue of the injection cylinder charges of molten metal, all of uniform volume so as to insure the production of uniformly perfect castings.

A further object of my invention is the provision of means of the type described which effects in operation an increase in the production rate of a die casting machine.

Other objects and novel aspects of the invention reside in certain details of construction, arrangement of parts, and mode of operation thereof, all of which will appear as the following description proceeds in view of the drawing in which:

Fig. 1 is an elevational view partly in cross section showing an embodiment of my invention in operative relation to a cold chamber die casting machine certain parts of which are illustrated.

Fig. 2 is a plan view of my automatic ladling device.

Fig. 3 is an enlarged cross sectional view taken substantially on line 3—3 of Fig. 1.

Fig. 4 is a cross sectional view of a ladle and showing in broken lines the position assumed for pouring a charge of molten metal into the sprue of an injection cylinder.

Fig. 5 is a cross sectional view taken on line 5—5 of Fig. 1.

Fig. 6 is an elevational view of a cam embodied in my invention.

5 Referring to the drawings, the numeral 10 indicates generally a preferred embodiment of my invention which may be supported on a bracket mounted on a die casting machine or on a floor stand located proximate to the receptacle of molten metal and the sprue of the injection cylinder. My invention comprises a cylindrical housing 11 supported on a bracket 12 suitably mounted on a portion of a die casting machine 13. It will be understood however that the housing 11 may be carried on a suitable stand supported on the floor.

20 Supported on the cylindrical housing 11 is a substantially box like cam housing 14 having a depending cylindrical portion 16 adapted to telescope over the upper portion of the housing 11.

The cam housing 14 is arranged for rotation about the axis of cylindrical housing 11 and is secured against displacement by a collar 17 which engages an annular shoulder portion 16.

25 A hydraulic cylinder 19 depends from the bracket 12 and is arranged so that its piston rod 21 extends into the housing 11. Connected to the piston rod 21 through a swivel joint 22 is a gear rack 23 which extends upwardly and is afforded lateral support by bearing blocks 24. An elongated member 26 having a cam groove 27 is attached to the inside wall of the housing 11 (Figs. 5 and 6), the groove 27 having a vertical lower portion, an offset vertical upper portion and an inclined intermediate portion connecting said two portions. A cam follower roller 28 is suitably mounted near the lower end of the gear rack 23 and is adapted to engage the walls of the cam groove 27.

30 Suitably supported in bosses 29 on the side walls of the housing is a shaft 31 on which are mounted for rotation a pair of spaced cam wheels 32 and 33 having cam grooves 34 and 36 respectively, in the sides thereof. A gear 38 similarly mounted is arranged between the wheels 32 and 33 and all are locked together for simultaneous rotation by bolts 39. As will be seen in Fig. 1, the gear rack 23 is in operative engagement with the gear 38 and in its travel passes between the 35 cam wheels 32 and 33. While the gear rack 23 is shown as the operative means for the gear 38, it is to be understood that a motor suitably geared to gear 38 may be used for driving said gear.

35 Pivotedly supported on shaft 41 mounted in the side walls of the housing 14 are a pair of arms 42 and 43 having located near their pivoted ends

cam follower rollers 44 receivable in and cooperating with cam grooves 34 and 36 of the cam wheels 32 and 33. The free end of each arm 42 and 43 is provided with a ball and socket joint 46. The ball portion of each joint 46 is threaded internally to receive the threaded end of a ladle carrying arm indicated generally by the numeral 48. The said arm comprises an inverted T-shaped member 49 having a longitudinal bore extending therethrough and counterbored at the lower end to provide a shoulder 51. A rod 52 having a head 53 at the lower end and threaded at the upper end is received in the bore with the head 53 abutting the shoulder 51. The threaded end of the rod 52 terminates in a squared end 55 and is in engagement with the ball portion of the joint 46. Longitudinal adjustments may be made by turning the squared ends 55 of rods 52 in either direction. The cross portion of the T-shaped member 49 is correspondingly bored therethrough and is arranged to accommodate a trunnion pin 54.

A ladle 56 shown in elevation in Fig. 4 comprises preferably an elongated body portion 57 provided with an integral cover 58, and having a pouring aperture 59 and a vent 60. Integral with the body portion 57 are two pairs of spaced upstanding perforated ears 61 in the perforations of which are received the trunnion pins 54, from which the ladle 56 is supported.

The ladle 56, T-shaped members 49 and pins 54, are preferably made of some suitable high temperature resisting ceramic or other material which will not be deleteriously affected by repeated immersions in the supply of molten metal contained in the melting furnace.

It is thought that the operation of this machine will be clearly understood from the foregoing, but briefly stated it is as follows, reference being had particularly to Figs. 1 and 4.

The arms 48 are adjusted to the correct lengths to properly position the ladle 56 with respect to the sprue 62 of the injection cylinder 63. At the beginning of the cycle of operations the gear rack 23 is substantially in the position shown in Fig. 1 at the lowermost position of its stroke. The operator admits hydraulic fluid into the conduit 20 connected to cylinder 19 which causes the piston rod 21 to travel upwardly and correspondingly to move the gear rack 23 which is guided in its travel by roller 28 in cam groove 27. This movement of the gear rack 23 causes simultaneous rotation of the gear 38 and cam wheels 32 and 33 thereby effecting pivotal movement of the arms 42 and 43 about the shaft 41.

In the sequence of operations in each cycle the cam wheels 32 and 33 first move the arms 42 and 43 in parallel relationship, to the position shown in broken lines in Fig. 1 at which position the ladle 56 while horizontally disposed is immersed in the pot of the melting furnace 64 and is substantially filled with molten metal. In the next stage the ladle 56 is elevated above the surface level of the molten metal and is then caused to be tipped or inclined a predetermined extent so that lip 59 is lowered and a predetermined quantity of molten metal is caused to be drained back into the melting furnace 64 leaving a desired quantity of molten metal in the ladle 56. It will be understood that adjustments may be made in members 48 to vary the degree of inclination and correspondingly to vary the quantity of molten metal retained in the ladle 56.

In the next stage of the cycle the ladle 56 may be caused to resume a horizontally level position

as above explained. At this point the rack 23 will have reached a position so that the cam roller 28 is substantially at the point where the cam groove 27 begins to incline from the vertical, as seen in Fig. 6. It will be apparent that continued upward movement of the cam roller 28 in the cam groove 27 will cause the gear rack 23 to rotate about its axis and correspondingly will cause the cam housing 14 to rotate about the axis of the cylindrical housing 11. The arms 42 and 43 are thus caused to swing the ladle 56 effecting a traverse of the ladle to a position for pouring the molten metal into the sprue 62 of the injection cylinder 63. In the next stage of the cycle the cam wheels 32 and 33 act to elevate the arm 43 above arm 42 which may be lowered to effect an inclination of the ladle 56 to the position shown in the broken lines in Fig. 4 whereby the molten metal is caused to be discharged into the sprue 62. At this point the piston rod 21 will have reached the limit of its upward travel and the operator then effects a reversal in the direction of the travel of the piston rod by admitting hydraulic fluid into conduit 30. It will be apparent that in the downward movement of the gear rack 23 the direction of rotation of cam wheels 32 and 33 is reversed and the sequence of movement of the ladle 56 is correspondingly reversed.

The cycle of operations hereinabove described may be controlled by an operator who initiates the forward and reverse movements of the hydraulic cylinder 19 as by the operation of a control valve. It will be understood however that means such as limit switches and solenoid valves may be utilized in connection with the structure herein described to effect continuously automatic operation of the apparatus, it of course being necessary to synchronize the movements of the ladle 56 with the operation of the injection piston of the die casting machine.

It is to be understood that the form of my invention herewith shown and described is to be taken as a preferred example of the same, and that various changes in the shape, size and arrangement of parts may be resorted to, without departing from the spirit of my invention, or the scope of the appended claims.

I claim:

1. A device for automatically ladling a liquid comprising a fixed support, a member carried on said support and rotatable about the longitudinal axis thereof, a pair of spaced arms pivotally attached at one end to said member, a cam rotatably mounted on said member and in cooperative engagement with each of said arms for pivotally moving said arms, a gear rotatable with said cam, a gear rack in operative engagement with said cam and disposed substantially co-axially with said support, a longitudinally extending cam groove associated with said support, a cam follower carried on said rack and in cooperative engagement with said cam groove, a ladle pivotally connected to the opposite ends of said arms, means for moving said gear rack axially so as to rotate said cam whereby to actuate said arms to move said ladle to selected positions, said rack in its axial movement being caused by said cam groove to rotate about its longitudinal axis thereby to rotate said cam and with it said arms and said ladle.

2. A device for automatically ladling a liquid comprising a fixed hollow support, a housing supported on said support and movable about the vertical axis thereof, a pair of spaced arms piv-

totally attached at one end to said housing, a gear journalled in the walls of said housing, cam means associated with said gear and rotatable therewith, said cam means being in cooperative engagement with said arms for pivotally moving said arms, a gear rack disposed substantially coaxially with said vertical axis and in operative engagement with said gear, a vertically extending cam groove associated with an inner wall surface of said support, a cam follower fixed to said rack and in cooperative engagement with said cam groove, a ladle pivotally connected to the opposite ends of said arms, means for moving said gear rack axially so as to rotate said cam whereby to actuate said arms to move said ladle to selected positions, said rack in its axial movement being caused by said cam groove to rotate about its longitudinal axis thereby to rotate said cam and with it said arms and said ladle.

3. A device for automatically ladling a liquid comprising a fixed support, a member mounted on said support for relative rotation, a pair of spaced arms pivotally connected to said member, a ladle suspended from said arms, cam means in cooperative engagement with each of said arms and journalled in said member, a gear rotatable with said cam means, a gear rack in operative engagement with said gear and movable longitudinally to rotate said cam means, second cam means associated with said support and cooperating with said rack to rotate the same about its longitudinal axis as it moves axially, means for actuating said gear rack axially to rotate said first mentioned cam means and said gear rack to

actuate said arms progressively to dip said ladle into a receptacle containing liquid, to tip said ladle to drain surplus liquid into said receptacle and to swing said ladle about the vertical axis of said support to a position for discharging said liquid.

4. A device for automatically ladling a liquid comprising a fixed support, a member mounted for rotation on said support, a ladle, means attached to said member for supporting said ladle, an elongated member movable axially of said support and keyed to said rotatable member, a vertically extending cam groove associated with said support, a cam follower associated with said elongated member and in cooperative engagement with said cam groove, means for moving said elongated member axially of said support so as to rotate said rotatable member and with it swing said ladle about the vertical axis of said support.
